UNITED STATES PATENT OFFICE.

SVEN MALCOLM BLANCH, OF WORCESTER, MASSACHUSETTS, ASSIGNOR TO FLEMING MACHINE COMPANY, OF WORCESTER, MASSACHUSETTS, A CORPORATION OF MASSACHUSETTS.

MEANS FOR HOLDING AND CENTERING GRINDING AND POLISHING WHEELS OR THE LIKE.

Application filed June 27, 1925. Serial No. 40,116.

- Ordinarily grinding and polishing wheels and discs are made with a central passage to fit the arbors on which they are to be mounted. These arbors vary in diameter. Therefore the user has to keep on hand a larger number of these wheels than he would otherwise and when he has to place one on an arbor he has to select one that will fit the particular arbor.
- The principal object of this invention is to provide means whereby all the wheels of the same size and having the same grinding or polishing characteristics will be made alike and there will be no difference in the central passage through them. This is done according to the present invention by providing centering discs for such wheels, all these discs being made to fit the wheels of all sizes and kinds and to support them, and the discs being constructed in sets having different diameters of passages through them so that any wheel can be put on any arbor merely by the selection of the right pair of discs. These discs are formed of sheet metal at comparatively small cost and as they vary only in the size of the passage through them for the arbor and as they can be used for all the various kinds of grinding and polishing wheels and discs, they do not involve any material expense to the user and a large number of them does not have to be kept on hand. Even if that is done for safety the expense is very small and the storage room required is also very little. The trouble of picking out from stock a wheel having the right sized hole is entirely avoided and the discs are picked out with reference to that feature alone so that the difficulty of selecting them is reduced very materially.
- Reference is to be had to the accompanying drawings, in which—
- Fig. 1 is a side view of a grinding wheel fitted up with a pair of discs for centering it on an arbor;
- Fig. 2 is a diametrical sectional view of the same on the line 2—2 of Fig. 1;
- Fig. 3 is a view similar to Fig. 2 of a buffing wheel mounted on the arbor and ready for operation; and
- Figs. 4 and 5 are diametrical sectional views of two of these discs of different sizes.
- The object of the invention has been explained in full and it is sufficient to say that the various grinding wheels 10 or cloth buffing wheels 11 are produced in the usual sizes and diameters and the former have a ring 12 at the center having a passage through it larger than any arbor on which they are likely to be placed. The ring 12 can be made of any convenient metal and a soft metal like lead is preferred. These rings are all bored or turned out at the center to exactly the same internal diameter for all shapes, sizes and kinds of stones, wheels and discs. In other words, all of them are made alike at the center so that if a user wishes to use a particular stone or wheel he does not have to pick through his stock and find one with a right center.
- For the purpose of centering these on arbors of different diameters, I provide a set of sheet metal discs 14 and 15. I have shown only two of these but as many sizes of them are required as there are arbors of different diameters in any given shop on which these stones are to be mounted. Each disc is essentially flat in the plane shown at the left in each of Figs. 4 and 5 and each is provided with an annular projection 16 leaving a cylindrical shoulder 17. These shoulders are of exactly the same diameter and size in all of the series of discs so that they will fit inside the rings 12 and 13 and accurately support them as shown in Figs. 2 and 3. Each disc is then curved backwardly into the main plane to form a circular flat surface 18 or 19 and then bent inwardly at the center to form a cylindrical wall 20 or 21. These cylindrical walls constitute bearings for the arbor A and they are made in different diameters on different discs for the purpose of fitting the different arbors.
- It will be obvious that two of these discs turned end for end will go into one of the rings 12 or 13, as shown in Figs. 2 and 3, and their shoulders 17 will support these rings centrally and accurately. The passages through the two discs are of course of the same size and receive this arbor and center the wheel just as well as if the passage were formed in the wheel itself. After the parts are set up, as shown in Fig. 2, they are put on the arbor A and secured in position in the usual way by collars 22 and 23 and a fastening nut 24, or in any other desired manner.

This constitutes a very simple way of supporting these wheels and results in a material economy for the user. He does not have to spend time picking over a set of six inch grinding wheels having a certain fineness to find one that will fit the arbor, but he can pick up any wheel he finds having the dimensions and characteristics that he desires and knows that will go on the arbor to 10 which he wishes to apply it. It will be obvious that when a man has to find the wheel having a certain diameter and a certain thickness, and also a certain fineness, and in addition has to find one with a passage 15 through it of a certain diameter, it may involve the loss of considerable time merely in searching for the right one, or else a rather elaborate system has to be employed. Furthermore he has to keep on hand an unnecessary 20 large number of these wheels. Of course he keeps in stock anyway wheels of the diameters, thicknesses and finesses that he desires but now with this invention he does not also have to keep four or five times 25 as many of them as would be required merely from the qualities mentioned. Furthermore, the selection of the discs that are necessary is a very simple matter because they vary in one particular only. They also 30 occupy very little space and their cost is almost negligible. Although I have illustrated and described only a single form of the invention and shown it as applied to only two wheels I am aware of the fact that 35 it is capable of general application and also of modification by any person skilled in the art without departing from the scope of the invention as expressed in the claims. There-

fore I do not wish to be limited in these respects but what I do claim is:—

1. The combination with a grinding or polishing wheel having a central passage through it larger than the arbor on which it is to be placed, of a pair of sheet metal discs having shoulders fitting the inner wall 40 of said passage and located opposite each other, each of said sheet metal discs having a bearing at the center to fit the arbor on which the wheel is to be applied.

2. The combination with a grinding or 45 polishing wheel having a central ring therein with a passage through it larger than the arbor on which it is to be placed, of a pair of sheet metal discs having circular shoulders near their circumferences fitting the 50 inner wall of said passage and located opposite each other in the planes of the two opposite flat faces of the wheel, each of said sheet metal discs having an integral bearing 55 at the center to fit the particular arbor 60 on which the wheel is to be applied.

3. As an article of manufacture, a sheet metal disc for the purpose described, comprising a flat circular plate having a cylindrical shoulder offset therefrom and having 65 a definite dimension and provided with a flat circular portion integral therewith extending from the inner end of the shoulder and provided with a second flat portion nearer the center and offset from said flat 70 portion and in the plane of the main portion of the disc and terminating in a cylindrical wall constituting a bearing.

In testimony whereof I have hereunto affixed my signature.

SVEN MALCOLM BLANCH.
